UNITED STATES PATENT OFFICE.

JOSEPH N. GILBERT, OF GRAND ISLAND, NEBRASKA.

APPARATUS FOR IMPARTING OSCILLATING MOTIONS TO ROTATING FANS.

Application filed July 3, 1926. Serial No. 120,452.

This invention relates more especially to motor driven fans and has for its object the following: a gearless oscillator that is adjustable by simple means independent of the speed of motor rotation, over a wide range of oscillating speed, and to any desirable arc of oscillation. Also adjustable to various horizontal planes of oscillation which change automatically with the change of direction of oscillation.

The oscillating motion is imparted by the unbalanced centrifugal pull of a weight attached by a crank to the rotating fan shaft co-operating with two small ratchets. The first ratchet permits the centrifugal pull to produce motion in one direction but resists motion in the opposite direction. The second ratchet permits and opposes motion in the reverse directions to the first ratchet. The first ratchet is in action during motion in one direction in the arc of oscillation while the second ratchet is in action during the reverse direction in the arc of oscillation. The active ratchet is automatically reversed at the adjusted end of the arc of oscillation.

The changing of planes of oscillation is accomplished by means applying the gyroscopic principle of precession which require that the fan and the motor frame are free to rotate in the vertical plane about a horizontal axle, within the limits of the adjusted vertical arc.

The torque tending to produce rotation in the horizontal plane about the vertical axle, causes a precessional rotation in the vertical plane, about a horizontal axle to the limit of the set arc, while the force tending to produce motion in the reverse direction in the horizontal plane causes reverse precessional motion in the vertical plane.

For a more complete description of my invention and explanation of the principle of operation, I will refer to the accompanying drawings, in which Fig. 1 is an elevation of a fan showing a sectional view of the oscillating device along *c*, *d*, *e*, *f*, *g*, Fig. 2, while Fig. 2 is a part end view of Fig. 1 showing a ratchet in contact with a ratchet slide. Fig. 3 is a sectional view on line *a*—*b*, showing a top view of the disk to which are attached the ratchet slides.

Fig. 4 is a modified form of my invention showing a different form and a different arrangement of the mechanical elements employed.

Fig. 5 is an end view of Fig. 4.

Fig. 6 is a sectional view on *h*, *i*, *j*, *k*, *l*, Fig. 4.

Fig. 7 is a sectional view on *m*, *n*, and *o*, *p*.

In Fig. 1, the motor frame 1 supports the rotor axle 2, to which is keyed the fan 3 and the crank 4 to which is attached the adjustable weight 5 held in position by bolt 6.

Said motor frame also supports the adjustable counterweight 7, held in place by 65 set screw 8. Attached to the motor frame are the axle bearings 9 and 10 which are respectively supported by the standards 11 and 12 attached to the rotatable vertical axle 13, having bearing 14 rotatable in the 76 bearing hub 15 attached to vertical support 16 resting on base 17.

Attached to the rotatable vertical shaft is the slide disk 18 to which are attached the slides 19 and 20 held in place respectively 75 by the set screws 21, 22 and 23, 24. Said ratchet slides have raised ends 25 and 26. The bearing hub supports the bolt 27 to which is attached the nut 28 holding in place ratchet hub 29 to which is attached the 80 ratchets 30 and 31. Also attached to the ratchet hub by bands 32 and 33 is the cylinder 34 containing the spheres 35 and 36. The arc of the elements rotatable in the vertical plane is limited by pins 37 and 38 while set 85 screw 39 clamps said elements at any desired angular position in the vertical arc.

Slots 40 and 41, 42, 43 in the slide disk permit the movement of the set screws to move the ratchet slides for the purpose of 90 adjusting the arc of oscillation.

In Fig. 4 the motor frame 44 supports the rotor shaft 45, to which is keyed the crank 46 on which is the adjustable weight 47, held 95 in place by bolt 48. Also keyed to the rotor shaft is the fan 49. To the motor frame is also attached the adjustable counterweight 50, held in place by the set screw 51.

Supporting the motor frame are the horizontal axle bearings 52 and 53 supported by 100 and rotatable in vertical standards 54 and 55, attached to the vertical axle 56 having bearing 57 rotatable in bearing hub 58, supported by rod 59 resting on base 60.

Attached to the motor frame is the ratchet arc 61 to which are attached the ratchet slides 62 and 63, held in place and adjustable in angular position by the set screws 64 and 65 movable in slots 66 and 67. Supported by the motor standards is the ratchet shaft bearing 68 having square section extension 69 supporting cylinder hub 70, held in 105 110

place by nut 71 and attached by bands 72 and 73 to cylinder 74 containing spheres 75 and 76. Said ratchet shaft bearing also has square section extension 77 supporting 5 ratchet hub 78 held in place by nut 79 and supporting ratchets 80 and 81.

The adjustable lugs 82 and 83 limit the arc of oscillation by intercepting the pin 84.

Operation.—The operation is as follows:

- 10 Assume rotation (either clockwise or counter-clockwise, Fig. 2) of the axle 2 with its attached crank 4, and weight 5. The unbalanced centrifugal force of the weight 5 exerts a continuous pull on 2. The direction of the pull at any instant is dependent upon the angular position of 5. At the instant shown the pull is in the direction of the arrow k . When 5 has rotated to the diametrically opposite position to that shown, the 15 pull will be in the reverse direction to arrow k . With ratchet 31 contacting with slide 19, all pulls in the reverse direction to k are resisted by 31, while the successive unresisted pulls in the direction k each produce motion 20 in the direction k . The resultant of these successive movements is counterclockwise rotation (looking in direction of arrow L) of all the elements rotatable about axle 13. As 25 this counterclockwise rotation continues the high end 25 contacts with 31, thereby rotating 31, hub 29 and cylinder 34 (see also Fig. 1) clockwise about 27, until spheres 35 and 36 roll to the right hand end of 34 thereby continuing the clockwise rotation of 30 all rotatable elements about 27 until ratchet 30 contacts with slide 20. Ratchet 30 resists pulls in direction of k but permits motion in the reverse direction to k . The resultant of 35 these successive movements in reverse direction to k is clockwise motion (looking in direction L) of all the elements rotatable about 13. This clockwise rotation will continue until the high end 26 contacts with 30 which 40 will start the counterclockwise rotation about 27, that will again bring 31 in contact with 19, thereby again starting counterclockwise direction of all elements rotatable about 13. The resultant of these successive 45 clockwise and counterclockwise rotations about 13 is an oscillating motion of all the elements rotatable about 13.

Oscillation in two alternate planes with precessional rotation about the horizontal axle.—In explaining the principle of oscillation in two planes I would call attention to the following gyroscopic principle of precession:

Torque tending to rotate a spinning mass about an axle perpendicular to the axle of 50 spin, produces precessional rotation about a third axle perpendicular to both the axle of spin and to the axle of applied torque. (See “Dynamics of Rotation” by A. M. Worthington, experiment 4, page 138. Also lower 55 half page 147 and top of page 148.)

In Figs. 1 and 2 assume the clamp 39 released so that all of the elements supported by the axle bearings 9 and 10, are free to rotate in a vertical plane to the limits of the interception of pins 37 and 38. 70

Also assume axle 2 with its attached elements to be spinning counterclockwise looking in direction of arrow n , Fig. 1. Then, as previously explained, with 31 bearing on 19 the rotation about 13 would be counterclockwise looking in direction of arrows L, 75 Fig. 2, also M, Fig. 1.

The yielding to the successive pulls that produce this counterclockwise rotation about 13, causes precessional rotation about axle 80 bearings 9 and 10 of all of their supported elements. (See Dynamics of Rotation, last half of page 147 and the two top lines on page 148.) This precessional rotation is counterclockwise looking at 10, Fig. 1. (See 85 Dynamics of Rotation rule for direction, page 139.) And will continue until 37 is intercepted by 12.

So long as this precessional rotation continues it opposes the yielding to the successive pulls that produce it. But when 12 intercepts 37 and the precessional rotation ceases then the opposition to yielding ceases, and the counterclockwise rotation about 13 90 proceeds more rapidly and continues until a 95 change of active ratchets, (from 31 to 30) takes place which reverses the direction of rotation about 13, as previously explained.

This reversal of rotation about 13 causes a 100 reversal of the precessional motion about 9 and 10 which continues until 38 is intercepted by 12, while the rotation about 13 continues until again reversed by a change 105 of active ratchets. (From 30 to 31.) This changing from 37 to 38 in contact with 12 110 changes the plane in which 2 and its attached elements oscillate, 37 and 38 are adjustable to various angular positions.

Oscillation in alternate planes with precessional rotation about the vertical axle.— 110 In Fig. 4, assume clockwise rotation of axle 45 and its attached elements looking in the direction of arrow R. With ratchet 81 bearing on slide 63, each successive pull of 48 when in the diametrical opposite position to 115 that shown as resisted by 81, while each pull of 48 when in the position shown produces motion. The resultant of these successive pulls being counterclockwise rotation, looking perpendicular to the plane of the paper, 120 of all the elements rotatable about 52 and 53.

The yielding of the elements rotatable about 52 and 53 to these successive pulls causes counterclockwise precessional rotation, looking in the direction of the arrow 125 S of all elements rotatable about 56. This precessional rotation about 56 opposes the yielding which produces it. But when 83 intercepts 84 and the precessional rotation about 56 ceases, then will the opposition to 130

yielding cease and the counterclockwise rotation about 52 and 53 will proceed more rapidly, until the high end of 63 contacting with 81, starts counterclockwise rotation, 5 looking perpendicular to the plane of the paper, Fig. 4 of all elements rotatable about bearing 68 (see also Fig. 6).

As this rotation about 68 continues, the spheres 75 and 76 will roll to the left hand 10 end of the cylinder 74, thereby continuing the rotation about 68 until ratchet 80 contacts with slide 62. As previously explained the change of ratchets, changes the direction to the opposition to the centrifugal pull, consequently a change to clockwise rotation 15 about 52 and 53.

As previously explained this change in direction or rotation about 52 and 53 the axle of applied torque causes a change of direction 20 about the precessional axle 56 to clockwise (looking in direction arrow S) precessional rotation which continues until 84 is intercepted by 82, which incident is as previously explained, followed by a change of 25 ratchets, with a consequent change about the axle of torque and also about the precessional axle.

Having described the mechanical combination 30 of my invention and the operation thereof, I claim:

1. Means for imparting an oscillating motion to a spinning weight, comprising in combination a spinning axle, a second axle about which said spinning axle is rotatable, 35 a weight unsymmetrically distributed in relation to the spinning axle and rigidly attached thereto, opposing means that oppose rotation of the spinning axle about said second axle, in clockwise direction only, a second 40 opposing means that oppose rotation about said second axle in counter-clockwise direction only and reversing means alternating the said opposing means at fixed points in the arc of rotation about said second axle.

2. Means for imparting an oscillating motion to a spinning fan; comprising in combination a fan attached to a spinning axle having an unsymmetrical distribution of weight 45 relative to the axis of spin, a second axle about which said spinning axle is rotatable, opposing means that oppose rotation of said spinning axle about said second axle in clockwise direction, a second opposing means that oppose rotation of said spinning axle about said second axle in counter-clockwise direction and reversing means alternating the said opposing means at fixed points in the arc of rotation about second axle.

3. Means for imparting an oscillating motion to a spinning fan and means for varying 50 the angular distance of the arc of oscillation; comprising in combination, a fan attached to a spinning axle having an unsymmetrical distribution of weight relative 55 to the axis of spin, a second axle about which

said spinning axle is rotatable, opposing means that oppose rotation about said second axle in clockwise direction, a second opposing means that oppose rotation about said second axle in counterclockwise direction, 70 reversing means alternating said opposing means at fixed points in the arc of rotation about said second axle and means varying the relative angular position of said fixed points. 75

4. Means for imparting an oscillating motion to a spinning fan and means of imparting to said spinning fan at the beginning of the clockwise oscillation, a precessional rotation in one direction in a plane perpendicular to the plane of oscillation and at the beginning of the counterclockwise oscillation a precessional rotation in the reverse to said one direction in the perpendicular plane, thereby causing an angular difference between the planes of the clockwise and the counterclockwise oscillations; comprising in combination a fan attached to a spinning axle having an unsymmetrical distribution of weight relative to the axis of spin, a second axle about which said spinning axle is rotatable, a third axle about which said spinning axle is rotatable, opposing means that oppose rotation about said second axle in clockwise direction, a second opposing means 80 that oppose rotation about said second axle in counterclockwise direction, reversing means alternating the said opposing means at fixed points in the arc of oscillation about said second axle, and means limiting the arc 85 of precessional rotation at fixed points in the arc of rotation about said third axle. 90

5. Means for imparting an oscillating motion to a spinning fan and means of imparting to said spinning fan at the beginning of the clockwise oscillation, a precessional rotation in one direction in a plane perpendicular to the plane of oscillation and at the beginning of the counterclockwise oscillation a precessional rotation 100 in the reverse to said one direction in the perpendicular plane, thereby causing an angular difference between the planes of the clockwise and the counterclockwise oscillations and means varying said angular difference; comprising in combination a fan attached to a spinning axle having an unsymmetrical distribution of weight relative to the axis of spin, a second axle about which said spinning axle is rotatable, a third axle 110 about which said spinning axle is rotatable, opposing means that oppose rotation about second axle in clockwise direction, a second opposing means that oppose rotation about 115 said second axle in counterclockwise direction, reversing means alternating the said opposing means at fixed points in the arc of oscillation about said second axle, and means limiting the arc of precessional rotation at fixed points in the arc of rotation about said third axle. 120

3. Means for imparting an oscillating motion to a spinning fan and means for varying 125 the angular distance of the arc of oscillation; comprising in combination, a fan attached to a spinning axle having an unsymmetrical distribution of weight relative to the axis of spin, a second axle about which

third axle, and means varying the angular position of the fixed points in the arc of rotation about said third axle.

6. Means for imparting to a spinning fan a precessional oscillating motion having an angular difference between the planes of the clockwise and the counterclockwise oscillations; comprising in combination a fan attached to a spinning axle having an unsymmetrical distribution of weight relative to the axis of spin, a second axle about which said spinning axle is rotatable, a third axle about which said spinning axle is rotatable, opposing means that oppose clockwise rotation about said third axle, a second opposing means that oppose counterclockwise rotation about said third axle, reversing means alternating the said opposing means at fixed points in the arc of rotation about said third axle and means limiting the arc of oscillation about said second axle.

7. Means for imparting to a spinning fan

a precessional oscillating motion having an angular difference between the planes of the clockwise and the counterclockwise oscillations and means varying said angular difference; comprising in combination a fan attached to a spinning axle having an unsymmetrical distribution of weight relative to the axis of spin, a second axle about which said spinning axle is rotatable, 25 a third axle about which said spinning axle is rotatable, opposing means that oppose clockwise rotation about said third axle, a second opposing means that oppose counterclockwise rotation about said third axle, reversing means alternating the said opposing means at fixed points in the arc of rotation about said third axle, means varying the angular position of said fixed points and means 30 limiting the arc of oscillation about said second axle.

JOSEPH N. GILBERT.
